UNITED STATES PATENT OFFICE.

RALPH E. NOBLE AND LOUIS E. MITCHELL, OF CHICAGO, ILLINOIS, ASSIGNORS TO MORGAN-
GARDNER ELECTRIC COMPANY, OF CHICAGO, ILLINOIS.

CRAB OR WINDLASS.

No. 907,635.

Specification of Letters Patent.

Patented Dec. 22, 1908.

Application filed April 17, 1907. Serial No. 368,784.

To all whom it may concern:

Be it known that we, RALPH E. NOBLE and LOUIS E. MITCHELL, citizens of the United States, and residents of Chicago, county of Cook, and State of Illinois, have invented certain new and useful Improvements in Crabs or Windlasses, of which the following is a specification.

This invention relates more particularly to 10 an improved form of windlass which is adapted for many purposes, but which is particularly for use in connection with a mining locomotive, and it also includes the combination of such locomotive with a crab 15 or windlass adapted for drawing up cars.

This invention also relates to a particular form of drum for a crab or windlass, and also to various details in the construction of the operative mechanism.

20 In coal mines equipped with electric haulage systems, it is frequently desirable to haul cars of coal from side-rooms which are provided with tracks but not provided with overhead conductors. Heretofore it has 25 been proposed to use gathering locomotives having flexible conductors which may be attached outside of the rooms and which may be wound up on reels on the locomotives as the latter go in and out of the side-rooms. 30 Such apparatus has not proven entirely satisfactory, and it is one object of the present invention to provide a locomotive with a suitable crab, the crab being provided with a line or cable which will reach into the room and can be connected with the car so 35 that the car may be pulled out by winding up the cable on the crab.

We have illustrated our invention in the accompanying drawings in which:

40 Figure 1 represents a side-view of an electric locomotive provided with our improved crab; Fig. 2 is a view partly in section and partly in elevation, showing our improved form of crab; Fig. 3 is a detail view, showing the method of locking the crab-motor body with the base; Fig. 4 is a detail plan-view, showing the driving gear and the clutch or connection between the main driving gear and the winding drum; and Fig. 5 is a top-plan view, showing the brake for the winding drum.

45 As shown in Fig. 1, 6 represents an electric locomotive of any ordinary or preferred form upon which is mounted at one end a crab or windlass 7 having a line or cable 8 for connection with the car or other device which is to be moved. The crab 7 is shown in detail in the succeeding figures and is provided with a base member 9 which is rigidly secured to the locomotive frame in any desired manner. This base is provided with an upwardly-extending cylindrical support 10 which furnishes a bearing for the winding drum 11. This winding drum forms one of the important features of our invention, and 60 differs from the ordinary winding drum in having a flanged or upwardly-dished head 12, as shown in Fig. 2. This flanged or dished head is made in this manner in order to cause the line or cable 8 to wind evenly on 65 the hub of the drum instead of piling up in a large spiral lying against the head, as frequently occurs in ordinary drums having flat heads, or heads which flare outwardly, or away from a plane passing at right angles 70 through the hub between the heads, thereby making a wider opening at the outer edge than at the hub.

The line 8 may be secured to the hub of 75 the winding drum in any desired manner, but we have provided a lug 13 for this purpose. As the drum is turned, the line will ride over the rounded edge 14 of the flanged head, which will thereby give the line an upward inclination so that it will start to wind 80 upwardly in a regular coil on the hub of the drum. When one layer has been wound on the hub, the line will ordinarily start to wind down without any tendency to gathering in a large spiral against the upper head, and 85 therefore the upper head is shown without any flange or bead; but, of course, it may be provided with such a flange to correspond with the lower head, as indicated in dotted lines. As the next layer is being formed 90 with the line moving down, the natural tendency is for the coil to continue until the bottom head is reached. Then, as above indicated, the flange or bead 14 will again cause the line to start properly to make the 95 next coil or layer instead of gathering around adjacent to the head. This improved winding drum, as applied to a locomotive according to our invention, is adapted to be driven 100 by an electric motor 15 which is provided 105 with a body 16 having a downwardly-projecting cylindrical bearing or support 17 closely fitting in the upwardly-extending support 10 of the base 9. In order to lock 110 the motor body in position, we have pro-

115

vided a locking device shown in Fig. 3. This locking device comprises a bolt 18 which fits in a hole 19 through the bottom of the support 10, and engages with a hole 20 in the lower end of the cylinder 17. This bolt 18 is operated by means of a screw 21 passing through a threaded hole 22 in the outer rim of the base 9 and engaging at its inner end with a lug or projection 23 on the end of the bolt 18. By means of this arrangement, the bolt 18 is securely held in position and at the same time can be readily operated when all of the parts are assembled.

The motor 15 is covered by means of a cap 15 fitting over the top of the body 16. The motor is preferably supplied with electricity from the same current or system which supplies the locomotive; but as the particular form of the motor and the wiring therefor do not constitute a part of this invention, they are not shown in detail in the drawings.

The armature 24 of the motor 15 is provided with a shaft 25 having a bearing in the lower end of the cylinder 17. A pinion 26 is secured to the lower end of this shaft, and this pinion engages with a gear 27 which is secured to a stub-shaft 28 having a bearing 29 in the frame 9, the hub of the gear also having a bearing in a bracket 30 secured to the frame 9 at 31. The upper end of the shaft 28 carries a pinion 32 which engages with an internal gear 33 which rests on a bearing ring 34 on the frame 9.

The internal gear 33 fits closely within a downwardly-projecting circular flange 35 on the winding drum. The winding drum is driven by the internal gear by means of a pawl or clutch device which is shown best in Fig. 4. The outer periphery of the gear 33 is provided with one or more notches 36. A pawl 37, pivoted at 38 between a bracket or support 39 and the head 12, is adapted to engage with said notches 36 in the gear 33. This pawl is provided with an outwardly-extending arm 40 which is pivoted at 41 to a ring 42 which extends entirely around the head 12 and is supported by means of brackets 43 on said head. It will be readily seen that when the ring 42 is moved in one direction, the pawl 37 will be thrown into engaging position, as shown in Fig. 4; and when the ring is moved in the opposite direction, the pawl will be thrown out of engaging position, a stop-pin 44 being provided to limit the movement in this direction. In order to hold the pawl in adjusted position, a spring toggle is provided, which consists of a link 45 having one end pivoted to the heel of the pawl 37 and having the other end engaging with a V-shaped slot in the end of the plunger which works in a socket 47 and is normally pressed outward by means of a spring 48. The action of this toggle is such that when the pawl is turned in the position shown, it will tend to hold the same in this

position; and when the pawl is turned to a non-engaging position, the toggle will tend to hold it in such position. By means of this clutch or pawl arrangement, the winding drum may be released from the driving mechanism so that it can be readily turned, as when it is desired to pay out the cable 8.

The upper head 11 of the winding drum is provided with a circular flange 49 which is adapted to be engaged by a brake-band 50, when, for any reason, it is desired to stop the movement of the winding drum or place a tension thereon. As shown in Fig. 5, a bearing 51 is bolted to the motor body 16. A lug 52 on one end of the brake-band 50 is pivoted to this bearing at 53. A threaded bolt 54 passes through the lug 52 and engages with a tapped hole in a lug 55 on the opposite end of the brake-band. An eccentric 56 is pivoted at 57 to the end of the bolt 54 and is provided with a handle 58. The arrangement is such that when the handle 58 is moved in either direction, the eccentric 56 will bear against the lug 52 and thereby tighten the brake-band 50 against the flange 49.

The advantages of our invention will be readily understood by any one familiar with the art, and we have herein particularly pointed out and described a preferred form of our invention; but it will be apparent that this form may be varied without departing from the scope of our invention, and therefore we do not wish to limit ourselves to this particular form; and it will also be apparent that certain features of our invention may be readily adapted for other uses or purposes than those herein described.

What we claim as our invention and desire to secure by Letters Patent, is:—

1. The combination of a base having a central vertical cylindrical support, a winding drum mounted on said support, a motor mounted in said support and having its armature shaft extending through said support, and gears connecting between said armature shaft and said winding drum for driving said drum.

2. The combination with a base having a vertical cylindrical support, a winding drum mounted on said support, a motor frame having a projection engaging with said support, an armature shaft extending through said projection, a train of gears connecting with said armature shaft, and means for operatively connecting the last gear of said train with said winding drum.

3. The combination with a winding drum, and a motor concentrically mounted on a single support of a train of gears connecting with the armature shaft of said motor, a clutch mechanism for engaging the last gear of said train with said winding drum and means for manually operating said clutch mechanism.

4. The combination with a winding drum and a motor concentrically mounted on a common frame, of a flange on said winding drum, an internal gear loosely fitting within said flange, means for driving said gear from said motor, and means for locking said gear with said winding drum to drive said drum.
5. The combination with a winding drum provided with a circular flange, of a driving gear having notches in the periphery thereof and fitting within said flange, a pawl on said flange adapted to engage with said notches, and means for manually throwing said pawl into and out of engagement with said notches.
- 10 6. The combination with an electric motor and a separate winding drum concentrically mounted on a vertical support, of a brake-band connected with said motor body and adapted to engage with said winding drum, and means for throwing said brake into and out of engagement with said drum.
- 15 7. A winding drum having the inner faces of the head arranged at substantially right
- angles to the hub portion, inwardly projecting rims or beads at the outer peripheries of 25 said heads, whereby the space between said rims will be less than the length of the winding portion of the hub, said rims acting as guides to control the movement of the cable.
8. A vertical winding drum having its bottom head provided with an upwardly projecting outer edge, said projection extending above the bottom winding portion of the hub of said drum and adapted to guide the rope upwardly after the coils have reached 30 35 the bottom of said hub portion.
9. A winding drum having its heads dished outwardly adjacent to the winding portion of the hub so that the space between the rims of said heads is less than the space 40 adjacent to the hub.
